UNITED STATES PATENT OFFICE.

HORACE TINSLEY, OF LEEDS, AND JOHN HENRY COX, OF OUTWOOD, ENGLAND, AS
SIGNORS TO DIAMOND COAL-CUTTER COMPANY LIMITED, OF STENNARD WORKS,
ENGLAND.

PROTECTION OF ELECTRICAL APPARATUS FROM OVERLOADS.

Application filed February 12, 1926, Serial No. 87,842, and in Great Britain September 17, 1924.

This invention relates to overload trip or cut-out mechanism of the solenoid and plunger type for the protection from overloads of electrical apparatus and connections thereto, more particularly apparatus which is used to control motor driven machinery. This mechanism however is as usually constructed set to allow for the sudden rush of current which occurs on closing a starting switch with a stationary motor and in such cases it is not possible to obtain a closer setting for the trip or cut-out mechanism than 150 per cent of full load, whereas in many cases cables and other parts of the electrical apparatus are undesirably heated by currents which are not quite sufficient to operate the trip mechanism. The chief object of the present invention is to allow in an improved manner for the primary rush 20 of current in the apparatus and consequently in the aforesaid solenoid and at the same time permit the trip or cut-out mechanism to be set to any desired approximation to full load.

In the present apparatus, therefore, means are provided whereby, at starting, the trip or cut-out mechanism is not permitted to act upon the usual initial rush of current and according to this invention the support or platform carrying one element of the overload cut-out solenoid and plunger mechanism is moved from the starting to the normal running position through a resilient connection and under the influence of 30 a delay action device, such as a dashpot, which determines the time taken for the said movement. In the starting position the plunger is sufficiently out of the solenoid to require an excess of current greater than the usual sudden starting current to produce a field in the solenoid sufficiently strong to move the plunger while, in the normal running position, the plunger is in a more favourable position for action by the solenoid field and can be operated by a current exceeding the normal full load by any predetermined smaller amount.

In order that the said invention may be clearly understood and readily carried into effect, the same will now be described more fully with reference to the accompanying drawing, which illustrates in section a typical construction of apparatus in accordance with this invention, the left and right hand

sides of the figure showing respectively the 55 starting and running positions.

A is the solenoid overload coil within which moves the plunger B, supported on the platform or crossbar C which is moved in the downward direction by the cam F on the switch operating spindle through lever G and push rod *g* and is moved in the upward direction by springs H through the medium of rods *h*, the speed of such movements being controlled by the dashpots J. 60 The time lag of the dashpots is variable through the pressure exerted by the springs H, which in turn is varied by position of the screwed rod *h* relative to the crossbar C. The platform is shewn at the left hand part 70 of the drawing in the position it occupies when the switch is off and when the switch is initially closed, while the right hand part of the drawing shews the platform in the position it assumes after a short space of 75 time after the switch is closed, such time being governed by the dashpots and being sufficient to allow the motor to get up to its full load speed.

The drawing illustrates an arrangement 80 with three solenoids, plungers and their individual dashpots together with two dashpots for the time lag on the sensitive varying device, but of course the number required may be varied or a single self-contained element may be employed.

The platform C moves parallel with the solenoid axis or axes, and according to its position it determines the length of the air gap inside the solenoid A between the plunger B and the top pole piece *e*². When the platform C is in its lower position as shewn at the left hand part of the drawing, the air gap is at its maximum and the pull on the plunger B due to the initial rush of current in the solenoid is not sufficient to raise the plunger from the platform and operate the trip or cutout mechanism while in the normal running position shewn at the right hand part of the drawing, the air gap between the plunger and pole piece is smaller and a smaller current will effect the operation.

The solenoids are mounted within the lower chamber of the casing E and are secured between the partition *e* and the bottom *e*¹ of the casing.

The solenoid operated plunger B is guided

within the solenoid A by a sliding rod b passing through the top hole piece and guiding nipple c² fitted to the inner wall e of the casing E and is connected by a rod b¹ at the lower end to a ball b² held in the dashpot D which slides upon the downwardly extending calibration tube d fixed to the casing within which tube the plunger B moves leaving a small clearance. The lower end of the dashpot D fitted to the platform or crossbar is adjustable to give any individual setting required and may be adjusted by a screw action and held in adjusted position by the spring detent d¹ engaging in one or other of the set of grooves d².

It will be seen that when the bar C is in the lower position indicated in the left hand part of the drawing the plunger B is lowered substantially beyond the position of maximum efficiency of the solenoid A so that a current considerably higher than normal would be necessary to raise it from the platform C through the action of the solenoid upon the core B. The platform or bar C is, therefore, arranged to take up this position when the switch is off and on starting the motor, while when the switch operating arm is moved over into normal running position the spring connection to the bar raises the latter into the position shewn in the right hand part of the drawing, but the movement is effected through the delay action of the dashpot and time is consequently given for the displacement into the normal running position so that the sudden starting rush of current is ineffective in operating the trip mechanism, while after the bar is raised the plunger B is in its more efficient position and a small excess of current over the normal will lift the plunger and operate the trip mechanism.

What we claim and desire to secure by Letters Patent of the United States is:—

1. In overload protection mechanism for electrical apparatus, a fixed casing, a solenoid and plunger cut-out device carried by the said casing, a support for one element of the solenoid and plunger device displaceable axially of the solenoid, means for moving the support from the starting to the normal running position of the mechanism and a delay action device which determines the time taken for said movement, which device is mounted between the said support and casing.

2. In overload protection mechanism for electrical apparatus, a fixed casing, a sole-

noid and plunger cut-out device, a displaceable support for one element of the solenoid and plunger device, means for moving the said support from the starting to the normal running position of the mechanism and a dashpot having two co-operating members of which one is carried by the said movable support and the other by the casing.

3. In overload protection mechanism as in claim 2, means by which the dashpot member carried by the support is adjustable relatively to the support.

4. In overload protection mechanism as in claim 2, means by which the dashpot member carried by the support is screwed adjustably into the said support and is provided with means retaining it in adjustable position.

5. In overload protection mechanism for electrical apparatus, a plurality of solenoid and plunger cut-out devices, a displaceable support carrying one element of each of the solenoid and plunger devices, means for moving the said support from the starting to the normal running position of the mechanism and a delay action device which determines the time taken for the said latter movement after the action of the said means.

6. In overload protection mechanism for electrical apparatus, a casing, a partition dividing the said casing into two chambers, a plurality of solenoids secured in one of the said chambers, plungers adapted to slide axially within the said solenoids, dashpot devices, one for each plunger and each having two co-operating members one of which is fixed in the outer wall of the said casing and has the said plunger sliding within it, a movable platform to which the other dashpot members are adjustably secured, connections between the plungers and their respective dashpot members carried by the said platform, springs tending to move the platform and attached members from a starting position to a normal running position for the apparatus, a cam mounted within the second chamber of the casing and a push rod connected to the dashpot platform and projecting into the said chamber, which push rod is adapted to be actuated by the said cam to displace the platform and associated members from one position to the other under the control of the springs and dashpots.

HORACE TINSLEY.
JOHN HENRY COX.
